Inventor:

Henry. Van. Horn John Woolridge
Harry J. Jones.

UNITED STATES PATENT OFFICE.

JOHN WOOLRIDGE, OF ROCKEFELLER, ILLINOIS.

CLOTHES-POUNDER.

SPECIFICATION forming part of Letters Patent No. 407,807, dated July 30, 1889.

Application filed March 16, 1889. Serial No. 303,561. (No model.)

To all whom it may concern:

Be it known that I, JOHN WOOLRIDGE, residing at Rockefeller, in the county of Lake and State of Illinois, and a citizen of the 5 United States, have invented a new and useful Improvement in Washing-Machines, of which the following is a specification, reference being had to the accompanying drawings, in which—

10 Figure 1 is a vertical section. Fig. 2 is a bottom view.

The object of my invention is to provide a combined pounder and rubber to be used in washing clothes, which I accomplish as illustrated in the drawings and as hereinafter described.

That which I claim as new will be pointed out in the claims.

In the drawings, A represents a bell-shaped 20 piece, which is preferably made of metal. a is a hub at the upper end of this bell-shaped piece A, the interior of which is screw-threaded.

B is a tube, the lower end of which is provided with a screw-thread by which it is secured to the hub a.

C is a handle, which is rigidly secured at the upper end of the tube B.

D is a hollow shaft, which may conveniently 30 be made from gas-pipe. As shown, the lower end of this shaft is screw-threaded on the outside.

E is a casting consisting, as shown, of a rim b, a number of arms c, and a hub d, the 35 spaces e between the arms c being open. The parts b c d are to be cast together, and the hub d is screw-threaded on the inside to receive the lower end of the shaft D. A key, pin, or other suitable known device may be

40 used for securing the casting E upon the shaft D in addition to the screw-threads, if desired.

F is a handle, which, as shown, is connected with the shaft D by means of an ordinary coupling f. As shown, the handle F is hollow. The lower end of the coupling f forms 45 a shoulder and stop which comes in contact with the upper end of the tube B.

G is a coiled spring located around the shaft D between the hubs a d.

The piece A forms the main portion of the 50 pounder, and the casting E is the rubber; but this casting also operates as a part of the pounder when the whole device is used for pounding.

In use the whole device can be used as a 55 pounder, the operator taking hold of the handles C and F, and when the device descends the rim of the bell-shaped piece A and the rim and arms of the casting E will all come in contact with the clothes, the same being 60 placed in a suitable receptacle, as usual. By allowing the bell-shaped piece A to remain at rest the operator using the handle F can partially rotate the shaft D and the casting E at the lower end thereof back and forth, 65 and then the casting E will perform the office of a rubber upon the surface of the clothes with which it is in contact, the spring G holding the rubber in contact with the clothes with sufficient force and yet allowing the 70 same to yield sufficiently to prevent material injury to the clothes.

When the device is used as a pounder, the air within the part A can escape up through the hollow shaft D and out through the hollow handle F, as indicated by arrows. I have provided holes in the shaft D near its lower end through which the air in A can escape. Either one or both of these outlets for air may be used at pleasure.

It is not necessary that the handle F be 75 made hollow. Provision for the escape of air from the hollow shaft D might be made by making a hole (indicated by g) in the coupling f. This coupling not only connects the 80 shaft D and handle F, but serves the purpose of a stop to limit the downward movement of the shaft D and rubber E.

I do not limit myself to the specific form of rubber E shown and described. The arms or 85 connections between the rim and hub of the rubber may be greatly varied in form and number.

What I claim as new, and desire to secure by Letters Patent, is as follows:

1. The combination of the hollow pounder A, tube B, secured to the hollow pounder A, hollow shaft D, provided with an opening at

or near each end for the passage of air from the inside of the hollow pounder, and a rubber E, secured to the hollow shaft D and capable of being rotated with such shaft, substantially as and for the purposes specified.

2. The combination of the hollow pounder A, tube B, handle C, hollow shaft D, handle

F, rubber E, spring G, and an outlet for air from the pounder A, substantially as and for the purposes specified.

JOHN WOOLRIDGE.
